UNITED STATES PATENT OFFICE.

HENRY FARKOUEH, OF BROOKLYN, NEW YORK.

PORTABLE RADIO RECEIVING SET.

Application filed May 21, 1923. Serial No. 640,335.

This invention relates generally to radio apparatus having more particular reference to a portable radio receiving set for receiving broadcasted speech and music, the invention having for an object the provision of a compact, self contained portable radio set in which the antenna takes the form of an enclosed special loop, the whole apparatus being contained in a single case. A further object of the invention is to provide a portable radio set characterized by sharpness of tuning and selection and the elimination of static and to provide a set which is very sensitive and will pick radio signals at any elevation, regardless where it is operated.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view showing my improved radio set with the case closed.

Fig. 2 is a similar view but showing the cover thrown open and the set ready for use.

Fig. 3 is a top edge view with parts in horizontal section.

Fig. 4 is a rear view of the panel board.

Fig. 5 is a transverse vertical sectional view taken on the line 5—5 of Fig. 4.

Fig. 6 is a diagram of the wiring circuit.

Fig. 7 is an end view indicating the means for supporting the set in proper receiving position.

Fig. 8 is a detail rear elevation showing the said supporting means.

Fig. 9 is a horizontal sectional view taken on the line 9—9 of Fig. 8.

As shown in the drawings I have embodied my invention in a readily portable unit whose enclosing casing comprises the body 10 and cover 11. These parts are of general construction such as is used in suit cases, and they may be made by fibre suitably reinforced at the corners and edges as shown. A handle 12 for carrying purposes is provided on that side of the case to which the cover is hinged, an ordinary lock 13 and hasps 14 being provided for the cover. On this latter side of the case a number of rubber knobs or feet 15 are provided to prevent jarring of the set when the case is set down.

The antenna for the set of the loop type is carried by the cover and consists of a wire 18 of suitable length and spacing arrangement looped around pins 19 carried by flat strips 20 secured to the inner face of the cover and extending diagonally from the corners thereof. The ends of this antenna connect to the loose wires which lead to the usual devices.

Hinged at one end to the end wall of the case 10 as at 25 is a panel board 26 which extends across the front of the case and carries the various elements of the set. The set here shown is of the type comprising a detector and three stages of radio frequency and 3 stages of audio frequency amplification, and to support the various tubes and transformers a shelf 27 is fixed to the back 60 of the panel by the brackets 28. The panel 26 and shelf 27 are preferably of hard rubber composition having a mahogany finish. The panel 26 also supports the loud speaker, comprising the horn 29 and the phone element 30, the mouth of the horn extending through the panel. The usual free cord 32 leads from the phone and has the plug 33 on its free end which engages with suitable jacks mounted on the panel board.

An objectionable factor common to most portable radio receiving sets appears to be the howling of the electron tubes, due to the mechanical vibrations of the loud speaker being transmitted to the grid elements of the tubes. Portable radio receiving sets usually have loop antennæ, which, of course have connections to the grid of the tubes, and if the vibrations of the loud speaker are permitted to reach the loop antenna, howling will result in the tubes. Also, if the loud speaker is so placed on the set so as to allow the mechanical vibrations to reach the tubes, howling will result. I have discovered that if the loud speaker is mounted in the plane of the front panel, as above described, and if a shelf, such as 27, is mounted at right angles to the plane of the panel, the mechanical vibrations in the panel set up by the loud speaker, are not very readily communicated to the shelf, and therefore the howling of tubes due to such vibrations are greatly reduced when mounted on said shelf. Furthermore with the loud speaker mounted in the panel, and the loop antenna mounted 105 110

within the box, the vibrations seem to be quite capable of reaching it, because of its great sensitivity to such vibrations. But with the loop mounted on the cover, and the 5 loud speaker on the panel, the vibrations affect the loop to a very much lesser degree.

The tubes which I prefer to employ are those known in the trade as model UV-199 and these are arranged in a row along the 10 shelf 27 with the detector tube, indicated at 35, in the centre, and the audio and radio frequency amplification tubes indicated respectively at 36 and 37 arranged on opposite sides of the detector tube. These tubes all 15 include the usual plate, grid and filament.

Upon the shelf 27, just to the rear of the tubes, are mounted the transformers which comprise three radio frequency transformers 38 and three audio frequency transformers 39. The radio transformers are preferably the Rasla Radio Service Laboratories RTS transformers, while the audio transformers are preferably two WD 12 Amplex Laboratories, 5 to 1 ratio 20 transformers and one Thordarson, 6 to 1 ratio transformer, for the third audio stage. The second stage audio transformers are placed at 90 degrees to the 1st and 3rd stage transformers. The set also includes three jacks 25 which are mounted on the panel 26 under the shelf 27 and which are connected to the detector and the different stages of audio amplification.

The loop 18 is tuned by a variable condenser 41 of the Varioden type, and a small vernier condenser 42 of the Chelton type. To stabilize the loop a 200 ohm potentiometer 43 is placed across the leads from the A battery. The filament circuit 45 to the entire 30 series of tubes is controlled by a 6 ohm rheostat inserted therein in the negative side, while like rheostats 46 in the positive side and 47 in the negative side respectively 40 control the individual circuits to the sets of 45 radio amplification and audio amplification tubes. A 30 ohm rheostat 48 in the positive side controls the filament circuit of the detector tube.

Of the jacks above referred to one double 50 circuit jack 50 is arranged in the detector plate circuit of the detector tube to cut in on the 3rd R. F. and detector tubes. A second double circuit jack 51 is arranged in the 55 3rd R. F. and two A. F. A single circuit jack 52 is arranged in the plate circuit of the 3rd A. F. stage to get the output of the whole seven tubes. The usual A and B batteries, indicated respectively at 53 and 54 are placed freely in the case 10 under the shelf 27.

In the use of the set the case is opened and the cover swung up to vertical position, while the body of the case is preferably arranged at a slight angle to the horizontal 60 65 as shown, the parts being arranged to have

the loop 18 at right angle to the path of the waves. The apparatus is then tuned up in the manner common with the loop, radio audio amplification sets.

To support the case 10 and cover 11 at the proper angles I provide a simple device which is in the form of a flat bar 60 which is slidably held when the set is not in use by a pair of cleats 61 and 62 fixed to the cover 11 and which then engage opposite ends of this bar. Another cleat 63 is fixed to the lower edge of the case body and is adapted to have the bar 60 projected therethrough to form a support or strut which holds the said body tilted. The bar 60 has a number of suitably spaced apertures 64 therein, while each of the cleats 62 and 63 has mounted thereon a pin 65 carried on the end of a flat spring 66 fixed at its other end to the cleat, this pin being adapted to take into selected ones of the said apertures to hold the parts in proper position. Each of these pins is formed with a knob or head 67 whereby they may be grasped when they are to be withdrawn from engagement with the bar. When the device is not in use the bar extends across the cover 11 and is held against sliding movement by engagement of the pin 65 on the cleat 62 with the lower opening 64 in the bar. In use the bar 60 assumes the position shown in Fig. 7, with the pins on the cleats 62 and 63 respectively engaged in suitable apertures in the bar.

I have found by experiment, and by actual reduction to practice, that a set of a high degree of efficiency, and capable of clearly receiving broadcasted speech and music up to a radius of approximately one hundred miles, covering a range of 200 to 600 meters wave length, depending on atmospheric conditions, can be contained in a case having dimensions of 20" long, 10" wide, and 6" deep, and with a weight not to exceed 20 lbs. The set is thus readily portable. The best unit quantities for the various instruments I have also found by actual test to be those indicated in Fig. 6. The loud speaker will produce a volume of sound capable of filling a room seating 500 people. It can be readily transported on automobiles, launches, and the like and will operate during travel. It constitutes briefly, a set characterized by neatness, compactness, efficiency and ease of setting up and general manipulation.

While I have described my portable radio receiving set to be used with the enclosed loop aerial, it may be used for receiving extreme long distance by connecting an outside aerial in series with one end of my loop aerial, in which case, the ground terminal on the panel board must be connected to an outside ground and the other end of the loop will stay connected with the aerial post mounted on the panel board.

Having thus described my invention what I claim as new and desire to protect by Letters Patent of the United States is as follows:

5. 1. A radio receiving apparatus, comprising a casing formed with a front panel, a shelf mounted thereto at right angles, and a hinged cover, radio mechanism mounted within said casing, and having the electron tubes mounted on said shelf, the loud speaker mounted on said panel board at one side of said shelf, with its mouth lying in said panel board, and the antenna in the form of a loop carried by said cover, whereby the 15 mechanical vibrations of the loud speaker are damped from reaching the grids of said electron tubes.
10. 2. A radio receiving apparatus, comprising a casing formed with a front panel, a shelf mounted thereto at right angles, and a hinged cover, radio mechanism mounted with said casing, and having the electron tubes mounted on said shelf, the loud speaker mounted on said panel board, with its 25 mouth lying in said panel board, and the antenna in the form of a loop carried by said
3. In a radio receiving apparatus, a portable case, a cover hinged thereto, and a strut normally carried by said cover and adapted to support the case tilted, and the cover vertical. 30
4. In a radio receiving apparatus, a portable case, a cover hinged thereto, and a strut normally carried by said cover and adapted to support the case tilted, and the cover vertical, and cleats on said case and cover engaging said strut. 35
5. In a radio receiving apparatus, a portable case, a cover hinged thereto, and a strut normally carried by said cover and adapted to support the case tilted, and the cover vertical, and cleats on said case and cover 40 engaging said strut, and pins carried by said projecting cleats into apertures in said strut. 45

In testimony whereof I have affixed my signature.

HENRY FARKOUEH.
